UNITED STATES PATENT OFFICE.

ELLIOTT LEWIS CHISLING, OF BROOKLYN, NEW YORK.

SUBMARINE RELIEF VALVE.

Application filed October 23, 1925. Serial No. 64,436.

This invention relates to submarine relief valves, an object of the invention being to provide a submarine with improved means whereby communication with imprisoned men in sunken submarines may be maintained, and also whereby air and food may be supplied as well as gas and liquid removed from compartments of the submarine.

10 A further object is to provide improved means of this character which are housed within the submarine leaving the outer wall or surface thereof free from obstruction to interfere with the operation of the submarine.

15 It is a well known fact that when submarines are sunk from one cause or another many lives have been lost due to the fact that air and food cannot be supplied to the 20 imprisoned occupants, and it is the broad object of my invention to so equip the submarine with my improved relief valves that imprisoned men in compartments can be supplied with air and liquid food for an 25 indefinite period, and also communication may be had with them at all times.

While my invention is particularly adapted for facilitating rescue work as applied to the lives of men, it is also applicable 30 to rescue work as applied to the submarine itself. For example, by employing my improved valves, the water in compartments can be removed and replaced by air or other gas which will assist in raising the submarine.

35 With these and other objects in view, the invention consists in certain novel features of construction and combinations and arrangements of parts, which will be more 40 fully hereinafter described and pointed out in the claims.

In the accompanying drawings—

45 Figure 1 is a fragmentary view in elevation of the outer portion of a submarine, showing my improved mechanism as applied thereto;

50 Figure 2 is a similar view, showing the covering plate removed;

55 Figure 3 is a similar view, showing the air lines or pipes connected with the valves;

Figure 4 is an enlarged view in section on the staggered line 4—4 of Figure 1;

Figure 5 is a sectional view, more or less 60 diagrammatic, illustrating my invention in connection with a sunken submarine.

1 represents a submarine having water

compartments 2 and compartments 3 for men and machinery. While I have illustrated my invention in connection with one of the compartments 3, it is obvious that 60 the invention may be applied to any or all of such compartments as well as to the water compartments 2, and I do not wish to be limited in this particular.

Specifically my invention includes a box 65 or casing 4, located inside the submarine, and having flanges 5 at its outer edges secured, preferably by rivets 6, to the outer plate 7 of the submarine. This plate 7 has an opening 8 therein preferably larger than 70 the interior dimension of the box or casing 4 and communicating therewith.

A covering plate 9 is provided to close this opening and lie flush with the outer plate 7 of the submarine. This covering 75 plate 9 is preferably formed at its edges with webs 10 projecting into recesses 11 in the flanges 5 with bow springs 12 interposed between the webs 10 and the bases of 80 said recesses 11, tending to force the plate outwardly when the plate is released.

Gaskets 13 are interposed between the inner face of plate 9 and the flanges 5 as well as between the flanges 5 and the submarine 85 outer plate 7, as clearly shown in Figure 4.

The box or casing 4 is formed of an outwardly projecting post 14 having a screw threaded bore 15 receiving a bolt 16. This bolt 16 is projected through an opening 17 in the covering plate 9, and a gasket 18 is located between the head 19 of the bolt 16 and the plate 9 so as to make the connection watertight. It will be noted that this bolt 16 performs the function of clamping 90 and securing the covering plate 9 in its closed position.

I also provide the covering plate 9 with air openings 20, normally closed by plugs 21 with gaskets 22 interposed between the heads of the plugs and the plate 9. When 100 these plugs 21 are removed they permit a by-pass between the interior of the box or casing and the water surrounding the submarine so as to overcome resistance to the removal of the plate 9.

105 Within the box 4 I provide a pair of valves 23 and 24, which may have any suitable means thereon for turning the same, but I have illustrated for the purpose ordinary wrench receiving enlargements 25 on the stems of said valves, so that these valves may be opened by an ordinary wrench.

The valves 23 and 24 are connected at their inner ends to pipes 26 and 27, respectively, said pipes projecting through the inner wall of the box or casing 4 and preferably screw-threaded so as to engage the internal threads in the openings, as clearly indicated.

Flanges or enlargements 28 are formed on the pipes 26 and 27 with nuts 29 located in side of the box or casing and co-operating with said enlargements to securely clamp the pipes and the valves in their proper positions. Suitable gaskets 30 are interposed between the enlargements 28, nuts 27 and the wall box or casing 4 to make the junctions watertight.

The outer ends of the valves 23 and 24 are formed with threaded nipples 31 to receive the ends of couplings 32 and the flexible pipes or hose 33 and 34. These pipes or hose 33 and 34 may be of any suitable length and have their inlet ends terminating in a relief boat 35, for a purpose which will be hereinafter explained.

While I have illustrated my improved valves as applied to one compartment of a submarine they of course may be applied to any or all of the compartments of a submarine, and I preferably terminate the pipe 26 in the upper portion of a compartment 3 while I extend the pipe 27 to the lower further corner of the compartment, as shown in Figure 5, for best results.

The operation is as follows:

Assuming that the submarine is sunk, as indicated in Figure 5, the diver is lowered into the water and locates a plate 9 or any desired number of these plates, and it is of course obvious that the plates may be colored or have distinguishing marks thereon which make it easy for the diver to locate them. When a plate is located, it is simply necessary for the diver to remove this plate 9, but before doing so he first removes any desired number of plugs 21 so as to prevent resistance to the movement of the plate. With an ordinary wrench he can turn the bolt 16 until the latter is released from post 14 and can then remove the plate 9. He then attaches the pipes 33 and 34 to the valves 23 and 24 and open communication is instantly had with the compartment of the submarine.

These pipes may be used as speaking tubes so that conversation may be carried on with the occupants of the compartments and their condition ascertained. If air is needed it will be supplied through one pipe and exhausted through the other, preferably in the

manner indicated in Figure 5. Liquid food can also be supplied through the pipes and, in fact, the pipes are useful for any purpose in the nature of rescue and sustenance means.

Such valves in connection with water compartments permit the water to drain off and air supplied to assist in raising the submarine, and where a compartment contains gas this likewise can be withdrawn. By the provision of such a valve mechanism I therefore not only prolong the life of the imprisoned seamen for a definite period but I also provide means to assist in raising the submarine.

Various slight changes and alterations might be made in the general form of the parts described without departing from my invention and hence I do not limit myself to the precise details set forth but consider myself at liberty to make such slight changes and alterations as fairly fall within the spirit and scope of the appended claims.

I claim:

1. In combination, a submarine having an opening in its outer plate, a box or casing, flanges on said box or casing secured to the inner face of the outer plate of the submarine adjacent the wall of said opening, said flanges having grooves therein, a covering plate located within the opening flush with the outer plate of the submarine, said plates having webs interlocking with said grooves, a central post in the box or casing having a screw-threaded bore, a plate securing bolt adapted to be projected through an opening in the plate and screwed into said bore, a pair of relief valves in the box or casing, and pipes communicating with said valves and extending into the submarine, one of said pipes terminating at the upper portion of the submarine compartment, and the other adjacent the floor of said compartment.

2. In combination, a submarine having an opening in its outer plate, a box or casing, flanges on said box or casing secured to the inner face of the outer plate of the submarine adjacent the wall of said opening, a covering plate located within the opening, flush with the outer plate of the submarine and engaging said flanges, a relief valve in the box or casing communicating with the interior of the submarine, a central post in the box or casing, and a bolt projected centrally through the covering plate and screwed into the post.

ELLIOTT LEWIS CHISLING.
